FIG. 2.

FIG. 5.

FIG. 6. Eugene W. Hawley
BY Frank D. Busser
ATTORNEY.

WITNESS:

Robt. Philpotch.

INVENTOR

UNITED STATES PATENT OFFICE.

EUGENE W. HAWLEY, OF PHILADELPHIA, PENNSYLVANIA.

TRUNK-LOCK.

1,178,920.

Specification of Letters Patent. Patented Apr. 11, 1916.

Application filed December 28, 1915. Serial No. 68,975.

To all whom it may concern:

Be it known that I, EUGENE W. HAWLEY, a citizen of the United States, residing at Philadelphia, county of Philadelphia and 5 State of Pennsylvania, have invented a new and useful Improvement in Trunk-Locks, of which the following is a full, clear, and exact description, reference being had to the accompanying drawings, which form a part 10 of this specification.

The object of my invention is to provide means for securing together the two members of a trunk at several points along its length by the operation of a single lock 15 which is opened and closed in the ordinary way.

It is known to provide a plurality of locking devices whose operation is controlled from a single lock; but such lock is 20 specially constructed and mounted and requires a double operation to cause it to effect complete locking or unlocking. It is also known to provide a plurality of hasp members hinged to the cover of the trunk, one 25 of which members is controlled by a key and is operated to move a locking contrivance into and out of operation with the other hasp members; but this construction necessitates the operation of both hasp 30 members in locking the trunk.

In my invention, I have simplified both the construction and the mode of operation, the latter involving merely a single movement of the locking hasp member in one direction to lock the trunk and a single movement of the locking hasp member in the opposite direction to release all the securing devices. The construction, moreover, is such as to permit of an arrangement 40 whereby the key-controlled hasp is located midway of the length of the trunk and controls securing devices at opposite ends. The construction also lends itself to the location of the key-controlled hasp near one end of 45 the trunk, which arrangement is more convenient in the case of a wardrobe trunk.

Preferred embodiments of the invention are shown in the accompanying drawings, in which—

50 Figure 1 is a front view of a trunk with my invention applied thereto. Fig. 2 is a sectional elevation looking from the inside toward the front of the trunk of Fig. 1. Fig. 3 is a detail view, partly in section, of 55 the key-controlled lock of the trunk of Figs.

1 and 2. Fig. 4 is a front view of a wardrobe trunk with my invention applied thereto. Fig. 5 is a sectional elevation looking from the inside toward the front of the trunk of Fig. 4. Fig. 6 is a detail view, 60 partly in section, of the key-controlled lock of the trunk of Figs. 4 and 5.

The trunk of Figs. 1 and 2 comprises a body *a* and a cover *b*. The locking hasp, which is of ordinary construction, is hinged 65 to the body *a* and has a flanged member *c* and a barrel *d*. When the hasp is closed, the flanged member *c* engages the escutcheon *f* on the cover *b* while the barrel *d* enters into registering orifices in the escutcheon and in the wall of the cover. The barrel contains the usual spring-actuated sliding bolts *e*, *e*, which, when the hasp is closed, engages the wall of the cover, thereby holding the hasp in locking position. 70 The bolts *e*, *e*, are released by a key.

The above construction is well known and need not be described in further detail.

On the inside of the trunk cover I have provided two longitudinally extending sliding bars *g* on opposite sides of the central lock. Each bar is pivotally connected to a hooked member *h*, one end of which is pivotally secured to a plate *i* secured to the cover wall, while the other or hooked end 85 is adapted for engagement with a loop *j* carried by a plate *k* secured to the trunk body. Rigid cleats *m*, secured to the cover wall, guide the bars in their sliding movement. The outer end of each bar has an 90 extension *n*, which is slideable in a bracket *o*. A coil spring *p* is confined between this bracket and the end of the bar and tends to move the bar inwardly toward lock.

Secured to and projecting beyond the barrel of the lock is a triangular shaped cam *r*, opposite cam faces of which, are adapted to engage the inner ends of the bars *g*, when the main lock is moved to its closing position as shown in the drawing, and move and hold the bars in their outer positions, in which positions the hook members *h* engage the loops *j*, thereby locking the cover and body of the trunk together at the center and at the ends. When the key is turned to release the bolts *e*, *e* and the hasp swung on its hinge away from locking position, the springs *p* act to move the bars *g* toward each other, thereby withdrawing the hooks *h* from the loops *j*. Thus, by 110

operating the regular locks in the ordinary way, the other securing devices will be simultaneously locked or unlocked, avoiding both a special manipulation of the main lock and a special operation of an additional locking hasp. It will be observed, also, that the lock need differ neither in construction nor operation from the ordinary lock and that the bar-actuating cam is added thereto without modifying its structure. The said cam is mounted directly on the locking barrel, in such central position that the outer edge of the cam alines with a line bisecting the hasp longitudinally, whereby the greatest power can be exerted by the cam with the least strain upon the hasp.

The construction shown in Figs. 4, 5 and 6 corresponds with that shown in Figs. 1, 2 and 3 except in the following particulars. There is only a single bar *g*, which operates two hook members *h* located respectively at the center and toward the bottom of the trunk. In place of the two faced cam *r*, there is substituted a single faced cam *s*, whose outer edge, however, is, like the outer edge of the cam *r*, located preferably centrally of the barrel *d*. The main lock is located toward the upper edge of the trunk,

which is the location best adapted for convenient manipulation.

Having now fully described my invention, what I claim is:

In a trunk, the combination with the two hinged sections thereof, of a main locking device hinged to one section on an axis extending longitudinally of the trunk and adapted to swing toward and engage the other section, a fixed locking member secured to the section to which the main locking device is hinged, a complementary movable locking member adapted to engage the fixed locking member, a longitudinally extending actuating bar for the movable locking member, said movable locking member and its actuating bar being carried by the other section of the trunk, and a cam carried by the main locking device and adapted, as the same is swung into engagement with the second section, to actuate said bar and thereby cause the movable locking member to engage the fixed locking member on the first named section.

In testimony of which invention, I have hereunto set my hand, at Philadelphia, on this 18th day of December, 1915.

EUGENE W. HAWLEY.
